UNITED STATES PATENT OFFICE

2,065,193

DEVICE FOR CONTROLLING COIN-OPERATED MACHINES

Bert E. Mills, Oak Park, Ill., assignor to Mills Novelty Company, Chicago, Ill., a corporation of Illinois

Application July 15, 1933, Serial No. 680,612

6 Claims. (Cl. 194—92)

This invention relates to devices for actuating coin-controlled machines and has for one of its objects the provision of a generally improved device suitable for operating pin ball games and like machines, a particular feature of the invention being the provision of means whereby it is made impossible for the player to operate the machine more than once, or a predetermined number of times, for each coin inserted.

10 A further object of the invention is the provision of a device adapted to operate in such manner that two plays, or machine operations, can be obtained for a single coin.

Another object of the invention is the provision 15 of a device having the latter feature which is so constructed that it can be readily adapted to permit but one play, or machine operation, for a single coin, if this arrangement should be preferred by the proprietor of the machine.

20 With the foregoing and other objects in view, which will appear as the description proceeds, the invention resides in the combination and arrangement of parts, and in the details of construction hereinafter described and claimed, it 25 being understood that various changes in the precise embodiment of the invention herein disclosed may be made within the scope of what is claimed, without departing from the spirit of the invention.

30 Referring to the drawings:

Fig. 1 is a side elevation of a device in which my invention is embodied, the same being shown installed upon a machine which is but fragmentarily illustrated;

35 Fig. 2 is a plan view of the same, one of the actuated members being shown in one position in full lines and in two other positions in dotted lines;

Figs. 3 and 4 are bottom plan views of the 40 device, showing the parts in different positions;

Fig. 5 is a detail view of the wire by which certain parts of the device may be locked to provide for single play operation; and

Fig. 6 is a plan view, partially broken away and 45 shown somewhat diagrammatically, of a pin board game with the device of my invention installed thereon.

Upon said drawings which illustrate the best manner in which I have thus far contemplated 50 applying the principles of the invention, the reference character 11 indicates a slide having an opening 12 therein to receive a coin, said slide being mounted in a guide 13 extending through a wall 14 of the machine on which it is mounted, 55 the opening 15 through said wall being covered

by a circular flanged disk 16 mounted on the guide 13, the latter having a bracket 17 secured thereto by a screw 18 and said bracket having a shelf portion 19 protruding forwardly from the disk 16 and serving as a support for the guide member 12.

The slide 11 has an upturned finger piece 21 at its outer end and is slotted, as indicated at 22, to receive a pin 23 protruding upwardly from a bottom plate 24 of the guide 13. Said pin 10 serves to limit the range of movement of the slide in manner which will be apparent.

A bracket 25 protrudes laterally from the forward end of said guide member 13 and carries an angle plate 26 attached to the wall 14 by 15 means of screws 27.

A detent 28, pivoted at 29 to a frame part 31 is provided above the slide and behind the disk 16, said detent being normally urged downwardly by a spring 32 secured at one end to a lug 33 20 on said detent and at the other end to a pin 34 on the top of the guide member 13. The forward end of the detent extends through a slot 35 in the top of said guide member and is adapted to enter the coin opening 12 in the slide to obstruct further forward movement in case said slide is advanced without a coin in said opening. The same action will occur if a slug having a hole 25 in the center thereof is inserted in the slide and the latter advanced.

If a magnetic slug should be inserted in the device it would be attracted by a magnet 36 mounted above the forward end of the slide 11 and would be held in the slide at the end of the forward stroke, returning therewith on the back 35 stroke and thereby preventing operation of the machine in manner which will hereinafter appear.

The slide 11 carries at its forward end a bar 37 which has ratchet teeth 38 in the side thereof 40 cooperating with a dog 39 pivoted at 41 to a frame part 42 to prevent retraction of the slide after it has advanced beyond a certain point until it has reached the forward end of its stroke. A spring 43, secured at one end to a tail part on 45 the dog 39 and at the other end to a lug 44 on the frame part 42, serves to urge said dog toward centered position.

The bar 37 at its forward end carries a pin or post 45 on the top of which there is a plate 46 50 held in place by a screw 47. A spring 48 connects said plate with a fixed post 49 on the frame and tends to draw the slide toward its rearward position.

The post 45 is so positioned that on forward 55

- movement of the bar 37 said post engages and operates certain parts of the machine to be controlled. In the particular adaptation of the invention shown in the drawings, said parts comprise a sliding board 51 of a pin game machine, generally indicated by the reference numeral 52 shown in Fig. 6; also a lug 53 depending from a bar 54 which is pivoted at 55 to the frame of the machine.
- 10 The board 51 has openings 56 therein adapted to be moved into and out of registration with openings 57 in a fixed board 58 on which pin cages (not shown) are adapted to be arranged, the balls, indicated in Fig. 6 by the reference character 59, being adapted to come to rest in one or another of the openings 57. The board 51 is normally held by a spring 61, connected at one end to a depending lug 62 on said board and at the other end to a frame member 63, in a 20 position in which the openings 56 in said board are out of registration with the openings 57 in the board 58. Upon forward movement of the actuating bar 37 the post 45 thereon engages the forward end of said board 51 and pushes the 25 latter rearwardly against the tension of the spring 61 until the openings 56 are brought into registration with the openings 57 in the board 58, at which time the balls drop through the aligned openings onto a slanting board 64 and roll into 30 a trough 65 at the forward end of the machine. Said trough slopes toward the side of the machine on which the balls are shown in Fig. 6 but said balls are obstructed by the forward end of a bar 67 which is positioned in said trough 65 and are 35 thereby prevented from dropping to a position from which they may be lifted by an elevating device 68 to the playing position from which they are in turn projected by a plunger (not shown) onto the table 58. A spring 69 connects the rear 40 end of the bar 67 with an eye 71 on the interior of the front wall 72 of the table 52 and tends to draw the forward end 66 of said bar 67 out of the trough 65. The bar 67 however is attached to the bar 54, at 13, and before the release of the 45 balls from the board 58 said bar 54 has been moved to the position shown in Fig. 6 through the action of the coin slide, as will be apparent from Figs. 1 and 2 of the drawings. When the lug 53 on said bar 54 has been advanced to the 50 dotted line position shown at the left in Fig. 2, a pivoted lever 74, which normally bears against the side of said lug, as shown in Fig. 1, is moved to the position shown in Fig. 2, this movement being accomplished by means of a spring 75 (see 55 Figs. 3 and 4) connected at one end to a lug 76 in the under side of said lever and at the other end to a fixed member 77 on the frame. Said lever 74 is pivoted at 78 to the under side of the guide member 13.
- 60 When the slide 11 reaches the full forward end of its stroke the coin will drop from the opening 12 in said slide into a carriage 79 positioned beneath the forward end of the slide and will be drawn rearwardly on the return stroke of the 65 slide by means of a pin 81 on the under side of the bar 37. The coin which is indicated in Fig. 3 by the reference numeral 80, is thereby caused to engage a flange 82 on a tail part 83 of the lever 74 thereby moving said lever to the position 70 shown in Fig. 3 and permitting the bar 54 with its lug 53 to be returned to the position shown in Fig. 1, this being the full line position shown in Fig. 2. This movement is caused by the spring 69 (see Fig. 6) and results in withdrawing the 75

bar 66 from the trough 65 allowing the balls 59 to drop into position for use.

The coin after passing the flange 82 on the lever 74 drops from the carriage 79 and is directed by a chute 84, formed on the member 17, 5 to a coin receptacle (not shown).

The device may be adapted to give either one or two plays, or machine operations, for one coin.

For the purpose of providing for "two-for-one" operation, I employ a lever 92 pivoted at 90 to 10 the frame and having a lateral projection 91 at its forward end adapted to enter beneath the dog or detent 28 when said lever is turned in counter-clockwise direction on its pivot by means of a spring 93 secured at one end to the forward part 15 of said lever and at the other end to the frame. The opposite end of said lever carries a member 94 pivoted for limited movement on said member 92, said member having a cam part 95 at its end, the lever being normally held in the position 20 shown in Fig. 2 by means of an upwardly extending lug 101 carried by the member 74 engaging a vertical portion 102 of said lever 92, a spring 97 connecting said member 94 and said lever 92 being provided to yieldingly pull 25 said member in counterclockwise direction (viewing Fig. 2). When said member is moved outwardly by the coin 80 as shown in Fig. 3, said lug 101 is moved forwardly sufficiently to clear said vertical part 102 allowing said member 92 to be rotated by the spring 93 in counterclockwise direction, causing the projection 91 to move under the dog 28 in manner which will be apparent from viewing Figs. 1 and 2. The slide may now be pushed forward a second time to 30 cause a second operation of the machine without inserting another coin. On this stroke, however, a pin 96 on the bar 37 will engage the cam part 95 on the dog 94 carried by the lever 92 and revolve the same back to the rest position 35 shown in Fig. 2. This will allow the lug 101 on the member 74 to again engage the edge of the vertical portion 102 on the member 92 locking said member in the rest position until moved 40 therefrom by the action of the coin on the member 74 on the next return stroke of the slide, as 45 previously described.

When it is desired to adapt the device for single operation, a wire hook 98, shown in Figs. 2 and 5, may be employed to hold the lever 92 in 50 the position shown in Fig. 2, the forward offset end of said hook being inserted in an aperture 99 in the bracket 26 and the opposite hooked end thereof being hooked over the lever 92, as shown in Fig. 2.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the construction hereinbefore described being merely a preferred embodiment thereof.

I claim:

1. A device for controlling coin-operated machines comprising a reciprocable coin slide having a coin-receiving opening therein, means operated by said slide upon a full stroke thereof for controlling the operation of the machine, a member adapted to enter said opening to prevent completion of the stroke of the slide in case there is no coin in said opening, said member being held in non-obstructing position by a coin in the opening, means operable by such coin upon the first 75

- return stroke of the slide after it has been advanced with a coin therein to lock said member out of action whereby to permit a second forward stroke of the slide without a coin therein, and 5 means operable upon the second return stroke of the slide to cause said locking means to be moved to inoperative position, said member being thereby freed to prevent a further advancing movement of the slide without a coin therein.
- 10 2. A device for controlling coin-operated machines comprising a reciprocable coin slide having a coin-receiving opening therein, means operated by said slide upon a full stroke thereof for controlling the operation of the machine, a 15 member adapted to enter said opening to prevent completion of the stroke of the slide in case there is no coin in said opening, said member being held in non-obstructing position by a coin in the opening, means operable by such coin upon 20 the first return stroke of the slide after it has been advanced with a coin therein to lock said member out of action whereby to permit a second forward stroke of the slide without a coin therein, means operable upon the second return stroke of the 25 slide to cause said locking means to be moved to inoperative position, and means whereby said locking means may be locked in inoperative position to thereby require insertion of a coin for each actuation of the device.
- 30 3. A device for controlling coin-operated machines comprising a reciprocable coin slide having a coin-receiving opening therein, means operated by said slide upon a full stroke thereof for controlling the operation of the machine, means 35 for normally obstructing movement of said slide in case no coin has been deposited in said opening, a member controlled by the slide and movable, upon the first operative stroke thereof after insertion of a coin, to position to hold said obstructing means out of obstructing position during a further operative stroke of the slide, thus 40 permitting a plurality of operations of the machine for a single coin, and means operable by the slide upon the final stroke thus permitted for releasing said obstructing means to permit the same to lock the slide against further operative movement unless another coin has been inserted therein.
- 45 4. A device for controlling coin-operated machines comprising a reciprocable coin slide having a coin-receiving opening therein, means operated by said slide upon a full stroke thereof for controlling the operation of the machine, means for normally obstructing movement of said slide in case no coin has been deposited in said opening, a member controlled by the slide and movable, upon the first operative stroke thereof after insertion of a coin, to position to hold said obstructing means out of obstructing position during a further operative stroke of the slide, thus 50 permitting a plurality of operations of the machine for a single coin, means operable by the slide upon the final stroke thus permitted for releasing said obstructing means to permit the same to lock the slide against further operative movement unless another coin has been inserted therein, and means whereby said member may be locked in inoperative position to thereby require insertion of a coin for each actuation of the device.
5. The combination with a coin-controlled machine including a movable control member, of a 20 coin slide, means operated thereby for moving said control member to a position in which it prevents operation of the machine, and a member for locking said control member in such position, said locking member being movable by the 25 coin upon the return stroke of said slide to cause the same to release said control member, the latter being thereupon movable to a position permitting the machine to be operated.
6. The combination with a coin-controlled pin 30 board game having a sliding board for supporting balls used in the playing of the game in the positions in which they come to rest upon completion of the game, and a control member for blocking the return of the balls to an initial playing position, of a coin slide, means operable thereby upon a forward stroke thereof for moving said board to release said balls and for moving said control member to a position in which it obstructs the balls after being released, thereby preventing 35 their return to said playing position, and a member movable upon the forward movement of the slide to a position in which it locks said control member in such obstructing position, said member being movable by the coin upon the return stroke of the slide to cause the same to release said control member, the latter being thereupon movable to a non-obstructing position permitting the balls to be returned to the playing 40 position.
- 50
BERT E. MILLS.
